UNITED STATES PATENT OFFICE.

CHARLES D. MENEELY AND HARRY A. CROWE, OF NEW YORK, N. Y.

TAG.

SPECIFICATION forming part of Letters Patent No. 735,397, dated August 4, 1903.

Application filed April 21, 1903, Serial No. 153,609. (No model.)

To all whom it may concern:

Be it known that we, CHARLES D. MENEELY and HARRY A. CROWE, citizens of the United States, and residents of New York, county of 5 Kings, and State of New York, have invented certain new and useful Improvements in Tags, fully described and represented in the following specification and the accompanying drawings, forming a part of the same.

10 This invention relates to certain improvements in tags.

It is desirable that tags of the character employed to seal receptacles shall be of such a character that they can be readily and 15 quickly applied to the receptacles, but cannot be removed by unauthorized persons without showing that the receptacles have been tampered with. For instance, it is customary for street-railway companies to supply conductors with string-tags, which are employed to tie up and seal the bags in which each conductor places the receipts for his tour of duty, the bags being deposited in a suitable receptacle in an office or other suitable place and 20 being removed from the receptacle by some person authorized to collect them, and it is desirable that such tags be so constructed that they can be readily and quickly applied to the bags, but cannot be readily tampered with without disclosing the fact. Furthermore, it is desirable in order to prevent waste 25 of cord that each tag have the proper amount of cord secured thereto.

The present invention has for its object to 30 produce an improved tag which can be readily and quickly applied to the article and which cannot be easily removed without destroying the tag.

With this and other objects in view the 35 invention consists in a certain construction and combinations, which will be hereinafter described and then specifically pointed out in the claims hereunto appended.

In the accompanying drawings, Figure 1 is 40 a perspective view of a bag having a form of the improved tag secured thereto. Fig. 2 is a plan view of the tag before it is applied to the article. Fig. 3 is a side view of the construction shown in Fig. 2. Fig. 4 is a sectional detail view on the line *a b* of Fig. 2. Fig. 5 is a sectional detail view on the line *c d* of Fig. 1.

In the drawings, 1 indicates a bag which may be used for containing money or other valuables, the bag being shown as closed by 55 the improved tag. The tag is provided with a body portion 2, which may have upon one of its sides blank spaces and proper inscription to indicate by whom the tag was applied to the bag and the date of its application. In 60 the preferred form of the construction the cord 3 will be secured to the tag. While this may be accomplished in any desired way, a cheap and effective way to do this is to secure the cord between its ends to the tag by 65 means of a retaining-piece of paper 4, which is pasted to the body portion of the tag on its rear side, both ends of the cord being thus left free. The tag is also provided with a locking-flap 5, which is integral with it, the 70 boundary between the body of the tag and the locking-flap being preferably defined by a crease 6, indicating the line of fold. The tag is further provided with a perforation 7, which is preferably surrounded by the usual 75 eyelet 8. In applying the tag the longer end of the cord is wrapped around the bag and secured by a knot, the bag being rolled, as shown, after which the cord is passed through the perforation, so that it is looped 80 through the perforation. In the preferred construction, furthermore, the tag will be provided with a second perforation 9, which, as shown, is located partly in the body of the tag and partly in the locking-flap. When 85 the tag is provided with this second perforation, the ends of the cord will be passed therethrough and then these ends will be carried in opposite directions around the sides of the tag and over onto the body of the tag, as indicated in dotted lines in Fig. 1. After the 90 ends of the cord have been thus positioned the locking-flap, which will preferably be provided with a coating of mucilage or paste, is folded upward and pasted to the retaining-piece, so that it securely fastens the ends of the cord in place. This construction makes 95 a firm and secure seal, so that the tag cannot be accidentally pulled off or tampered with without detection.

While the construction illustrated embodies the invention in its preferred form, it is to be understood that changes and variations may be made therein without depart-

ing from the invention. The invention is not, therefore, to be limited to the specific construction herein shown and described.

What is claimed is—

- 5 1. In a tag, the combination with the body portion having a perforation, of a cord having one end secured to the body portion, said cord being adapted to be looped through the perforation, and a locking-flap adapted to be secured to the body portion and overlying the ends of the cord, substantially as described.
- 10 2. In a tag, the combination with the body portion having a perforation, of a cord, a retaining-piece by which the cord is secured to the body portion, said cord being adapted to be looped through the perforation, and a locking-flap adapted to be pasted to the body portion and overlying the ends of the cord, substantially as described.
- 15 3. In a tag, the combination with the body portion having two perforations and a locking-flap, of a cord adapted to be looped through one perforation and having its ends passed through the other perforation and over onto the body portion of the tag, the locking-flap being adapted to be pasted to the body portion and overlying the ends of the cord, substantially as described.
- 20 4. In a tag, the combination with the body portion, said body portion having a perforation through which a loop of cord is adapted

to be passed and a second perforation through which the ends of the cord are adapted to be passed and having a locking-flap, of a cord secured to the body portion of the tag whereby the cord is adapted to be looped through one of the perforations and both ends passed through the other perforation and carried in opposite directions around the end of the tag to a position between the locking-flap and the body of the tag, substantially as described. 35

5. In a tag, the combination with the body portion having a perforation near one end and a perforation near the other end and a locking-flap, of a cord, and a retaining-piece operating to secure the cord to the tag between its ends, whereby the cord is adapted to be looped through one perforation and have both its ends passed through the other perforation and carried around the end of the tag and over onto the body portion, the ends of the cord being secured beneath the locking-flap, substantially as described. 45 50

In testimony whereof we have hereunto set our hands in the presence of two subscribing witnesses. 55
